CUSHIONING MECHANISM

Leverett M. Clark, Snyder, N. Y.

Application July 19, 1935, Serial No. 32,228

14 Claims. (Cl. 213—32)

This invention relates to cushioning mechanism of the energy absorbing type and is concerned more particularly with a novel friction cushioning mechanism which may be employed for various purposes, as, for example, as a draft gear for railway equipment, or in connection with buffers, trucks, etc. While the new cushioning mechanism has a wide range of utility, it may be employed to especial advantage as a draft gear, and accordingly an embodiment of the invention for that purpose will be illustrated and described to make clear the principles of the invention.

As is well known, draft gears are commonly employed on railway vehicles to protect their structures and lading against shocks to which they are subjected during switching and when in train service, and one of the objects of my invention is to provide a cushioning mechanism which is suitable for use as a draft gear and which has high energy absorption, low resistance, smooth action, and sustained initial compression. In addition to these features, the new device is of rugged construction so that it has a long life, and it is of relatively light weight.

The new cushioning mechanism comprises a casing preferably cylindrical in form which encloses the operating elements of the device and is provided in one end with the friction generating surface of frusto-conical formation. Friction shoes lying side by side in a circular series engage the friction surface, and within the group of shoes is an actuating plunger which has parts interengaging with parts on the shoes. At the inner end of the group of shoes is a flat ring which has parts engaging with the shoes so as to maintain the latter in proper circumferentially spaced relation, and a partially compressed coil spring within the casing engages the inner face of the ring and tends to force it and the shoes outwardly. The force of the spring is transmitted from the shoes through the interengaging parts to the plunger and the outward movement of the latter is limited by appropriate means, such as a tie bolt.

The interengaging parts on the shoes and plunger are of such form that when a compressive force is applied to the device, the shoes move inwardly along the friction surface, generating friction and compressing the spring. When the force is removed, the expansive stresses in the casing react against the shoes and effect the release of the device and the spring thereupon restores the parts to their original position. While the spring functions to maintain the initial compression of the cushioning mechanism and to

maintain the device at its normal full length, it does not react against the plunger and therefore does not function as a release spring. In order that the expansive stresses of the casing may be effective to release the device, the interengaging parts on the shoes and plunger are of angular formation and the angles involved are of the type known as "self-releasing" angles.

The spring employed may be either single or double and it is so arranged that the torsional force of the spring, exerted during its operation of restoring the device to normal condition after removal of a compressive force, acts on the ring and causes the ring to move circumferentially. This movement of the ring causes the group of 15 shoes to be shifted circumferentially with the result that successive inward movements of the shoes along the friction generating surface are on different parts of the surface and the formation of grooves which extend lengthwise of the surface and are of arcuate cross-section and which would result in improper functioning of the device under certain conditions hereinafter described, is prevented.

For a better understanding of the invention, reference may be had to the accompanying drawings in which—

Fig. 1 is a view in longitudinal section of the device as used as a draft gear;

Fig. 2 is a view similar to Fig. 1, showing the device under compression and with certain of the parts illustrated in elevation;

Figs. 3 and 4 are sectional views on the lines 3—3 and 4—4 of Fig. 1, respectively;

Fig. 5 is a fragmentary sectional view showing 35 the shoes in elevation;

Fig. 6 is an end view of a part of the device;

Fig. 7 is a view of the inner surface of one shoe; and

Fig. 8 is a sectional view on the line 8—8 of 40 Fig. 7.

Referring now to the drawings, the device is illustrated in Fig. 1 as comprising a casing 10, preferably of cylindrical formation, since a casing of that shape permits expansive stresses to 45 be readily equalized so that the casing, even though of light weight, is not liable to burst. At one end, the casing is closed and this end of the casing is provided with flanges 11 and 12 of generally rectangular shape, as shown in Fig. 50 3. In the installation shown in Fig. 1, the casing lies between the usual draft sills 13 of a railway car and the flanges 11 and 12 engage stop lugs 14 secured to the inner surfaces of the sills. The opposite end of the casing is open and adjacent 55

this open end, the inside of the casing is formed with a friction-generating surface 15 of frustoconical formation. This surface is of sufficiently large area to obtain the necessary cushioning capacity without undue abrasion, and the inward taper of the surface is selected to provide the proper rate of capacity increase of the device in operation.

Mounted within the casing at the open end 10 are friction shoes 16, each of these shoes being arcuate in section and having its outer curved surface in contact with the friction-generating surface 15 of the casing. The curvature of the friction surfaces of the shoes is so related to the 15 curvature of the friction-generating surface 15 in the casing, that maximum contact is obtained when the shoes are at the limit of their inward movement into the casing. The shoes are arranged in a circular series and each shoe has 20 angular projections 17 on its inner surface, the shoes as illustrated being provided with three such projections which extend across the shoe, each projection having sloping surfaces 18 which are convergent toward the top of the projection. 25 At its inner end, each shoe is provided with a notch 19, and at the inner end of the group of shoes is a flat ring 20 which is formed with a circular stiffening rib 21 from which extend radial ribs 22 on equal spacing with each rib 22 30 entering a notch 19 in a shoe. A coil spring 23 within the casing bears at one end against the closed end of the casing and at the other end against the inner surface of the ring 20, and this spring may be single, or double, as illustrated. 35 If a double spring is employed, both component parts have the same twist. If desired, the end of the spring which bears against the closed end of the casing may have an offset portion 24 which enters an opening 25 in the end wall of the casing.

Inside the group of shoes is an actuating plunger 26, which is of generally cylindrical formation and has circumferential corrugations 27 on its outer surface. Each corrugation lies 40 between adjacent projections 17 on the shoes and has sloping surfaces 28 corresponding to the sloping surfaces 18 on the projections. The plunger has an end portion 29 of reduced diameter which extends through a central opening in the ring 20 and serves as an axial guide for both the ring 45 and the spring. A tie bolt 30, the head of which is seated in an opening in the end wall of the casing, passes through a bore in the end portion 29 and has a nut 31 on its end, the nut lying 50 inside and engaging a portion of the plunger. 55

When employed as a draft gear, the device is used with the usual front follower 32, the rear face of which normally engages the end of the plunger 26, and the usual coupler shank 34 bearing 60 against the front face of the follower 32 is provided. The forward end of the casing 10 is engaged by the rear face of front follower 32 when the device is fully closed as shown in Fig. 2.

As assembled, the friction shoes 16, which are 65 preferably six in number so as to obtain uniform pressure distribution, project out of the casing, and the inclined surfaces thereon are forced into contact with corresponding surfaces on the plunger by the force of the spring 23 transmitted to the shoes through the ring 20. The outward movement of the plunger being limited by the tie bolt 30, the shoes are forced radially outward 70 against the casing. The compressed spring combined with the pressure of the shoes against the casing interior establishes the initial resistance 75

of the device. Since the free length of the spring is considerably greater than its length when the device is in normal or released position, it is obvious that the result of any normal "set" combined with such lengthening as is occasioned by the outward movement of the shoes compensating for casing bore wear will not materially effect spring loading values. Consequently, the initial resistance of the device will remain essentially uniform throughout its life. This effect could 10 not be obtained with springs of high ultimate capacity such as are required in the majority of high capacity friction devices. 5

In the operation of the device, its overall length is shortened by the plunger being forced 15 into the casing, carrying the shoes with it and thereby generating friction. In draft, the casing 10 is moved over the shoes 16 and plunger 26 by the rear end of yoke 35 being drawn forward by the coupler 34, while in buff, the shoes 16 and 20 plunger 26 are moved into the casing 10 by the coupler shank 34 acting against the follower 32. The inward movement of the plunger and shoes takes place against the resistance of the spring and the force of the spring acting through the 25 angular formations of the shoes and those on the plunger tends to force the shoes radially outward. Friction between the shoes and conical surface in the casing is developed in part by the action of the spring tending to force the shoes outwardly 30 and in part by the decreasing diameter of the surface along which the shoes move. The angular formations on the shoes and plunger are such that there is a radial clearance at all times between the shoes and plunger so that the mechanism can be fully closed without jamming which would otherwise result in failure to release. 35

In the normal or released position of the mechanism, the helical spring exerts a pressure of the order of 6,000 to 7,000 pounds and this 40 pressure, acting through the interengaging projections of shoes and plunger, forces the former radially outward against the conical surface in the cylinder, and offers resistance to inward movement of the shoes and constitutes what is known 45 as the "initial compression" of the mechanism. Whenever a force of sufficient magnitude is applied to the cushioning device to overcome its initial compression, the plunger, shoes, and spacing ring, are moved into the casing with the result that the casing is subjected to expansive 50 stresses. During the inward movement of the shoes, the radial pressure tends to increase until the reaction of the casing under expansion, operating through the coacting angular formations 55 on the shoes and plunger, overcomes the static adhesion and forces the shoes inwardly with respect to the plunger. This results in the reduction of the effective outside diameter of the group of shoes and correspondingly reduces the 60 pressure of the shoes against the casing. In certain prior devices of this sort, the static adhesion of the parts is so great that the inward movement of the friction generating element is delayed to a point near complete closure of the 65 device with the result that high radial pressures are exerted upon the casing, and forces, sometimes of the order of 600,000 pounds, are transmitted to the vehicle structure.

In the device of this invention, the static adhesion between the coacting angular formations on the shoes and plunger is of a relatively low value because of the balanced pressure distribution, and the slipping of the shoes relative to the plunger may occur several times during the com- 75

- pression of the device. When the compressive force is removed, the expansive force of the casing acts through the shoes to cause the plunger to be expelled slightly with respect to the shoes.
- 5 The pressure of the shoes against the casing is thereupon reduced to that arising from the action of the coil spring, and since the frictional engagement of the shoes and casing can be overcome by that component of the spring force which
- 10 is directed outwardly, the spring acts at once to restore the operating parts to their normal or release position.

The spring employed has a relatively high capacity in the normal condition of the device and its capacity does not greatly increase during the closing of the cushioning mechanism, with the result that a relatively small amount of energy is stored in the spring during closure of the device and subsequently delivered in the form of 20 recoil during release. The maximum capacity of the spring may be approximately 12,000 pounds as compared with 25,000 to 45,000 pounds capacity of springs in similar cushioning devices of the former constructions.

25 The use of a spacing ring interlocked with the shoes and so acted upon by the spring as to cause the shoes progressively to assume different positions of engagement circumferentially with the friction surface in the casing in successive operations of the device, avoids the possibility of the shoes wearing grooves lengthwise of the friction surface and of a cross-sectional shape corresponding to that of the shoes. In devices in which such groove wear takes place, the expansive stresses ultimately become unbalanced and the casing may prematurely fail in service. Also in devices in which the friction surface on the casing becomes so grooved, a blow of unusually 30 high magnitude will occasionally cause the shoes to become displaced circumferentially with the result that the shoes may contact in part with the intervening ridges of relatively small area. During subsequent closure of the mechanism, sufficient heat may be developed on the resultant small areas of contact to cause the shoes and casing to become partially welded together due to excessive heat, with the result that the mechanism fails to release.

In the present device, the spring acting on the 35 spacing ring causes no circumferential movement of the latter during closing of the device because the pressure of the friction shoes against the friction surface on the casing offers too great a resistance. Accordingly, during closing, the torsional movement of the spring results in a slippage of the spring over the face of the ring since the ring is of a greater surface hardness than the casing, and thus the coefficient of friction is lower. During the release of the cushioning mechanism, the radial pressure of the shoes against the casing surface is reduced with the result that the torsional movement of the spring causes the ring to rotate slightly, carrying the shoes with it. This action prevents the formation 40 of ridges on the interior wall of the casing and insures continued uniformity in operation of the mechanism.

The device of the application affords an additional advantage in that it may readily be assembled and taken apart without the application of high pressures. With other types of devices of the same general character, pressures ranging from 25,000 to 75,000 pounds must be applied to compress the devices sufficiently against their 45 combined spring and frictional resistance to per-

mit the removal of the nuts, keys, or other means that are used to hold the devices at their normal assembled lengths. Such relatively high pressures usually require that the devices be delivered to shops where hydraulic presses or similar facilities are available for the application of the pressures, whenever the devices are to be taken apart. This involves expenditures of both time and money.

5 In the device of the application, it will be noted that the friction shoes project outwardly beyond the open end of the housing and the direct inward movement of the shoes is resisted only by the helical spring acting through the spacer ring. Accordingly, by applying pressure directly to the 10 ends of the shoes by means of a suitable device such as a sleeve or the like, the shoes can be forced inwardly to an extent sufficient to permit ready removal of the nut 31 on the end of the tie bolt and the pressure required for this purpose is of the order of 6,000 to 7,000 pounds. The use of such a sleeve permits the pressure to be applied directly to the shoes and not to the end of the plunger, and a suitable sleeve for the purpose may have a window or other means through 15 which access to the tie bolt nut may be had. The sleeve may be employed both for dismantling and assembling the device and by its use, these operations are simplified and made relatively easy.

20 I claim:

1. A cushioning mechanism of the friction type, which comprises a casing, friction shoes therein, a central actuating plunger extending within the group of shoes, a plurality of cooperating wedging surfaces on both the inner surfaces of said shoes and the outer surface of said plunger, said surfaces being distributed along the length of said shoes and plunger, a ring engaging said shoes and maintaining them in proper circumferentially spaced relation, and a spring within said casing engaging said ring and resisting inward movement thereof.

2. A cushioning mechanism of the friction type which comprises a casing, friction shoes therein, a central actuating plunger extending within the group of shoes, a plurality of cooperating interengaging wedging parts on both the inner surfaces of said shoes and the outer surface of said plunger, said surfaces being distributed along the length of said shoes and plunger, a ring engaging the shoes and maintaining them in proper circumferentially spaced relation, and a spring within said casing engaging said ring and resisting inward movement thereof.

3. A cushioning mechanism of the friction type which comprises a casing, friction shoes therein, a central actuating plunger extending within the group of shoes, a plurality of interengaging wedging parts on both the inner surfaces of said shoes and the outer surface of said plunger, said parts being disposed along the length of said plunger and shoes, a ring at the inner ends of said shoes interlocked with the shoes and maintaining them in proper circumferentially spaced relation, and a spring within said casing engaging the ring and resisting inward movement thereof.

4. A cushioning mechanism of the friction type which comprises a casing, a friction surface in 70 said casing, friction shoes in the casing contacting with said surface, a central actuating plunger, said plunger and shoes having a plurality of engaging surfaces inclined to the axis of the casing, and distributed along the length of said shoes 75

and plunger a ring engaging said shoes and maintaining them in proper circumferentially spaced relation, and a spring within said casing engaging the ring and resisting inward movement thereof.

5. A cushioning mechanism of the friction type, which comprises a casing, a friction surface in said casing, friction shoes in the casing contacting with said surface, a central actuating plunger 10 extending within the group of shoes, said shoes and plunger having engaging surfaces inclined to the axis of the casing at self-releasing angles, said engaging surfaces lying both on the outer surface of said plunger and on the inner surfaces of said shoes and being distributed lengthwise thereof, a ring at the inner ends of said shoes engaging said shoes and maintaining them in proper circumferentially spaced relation, and a spring within the casing engaging the ring and resisting inward movement thereof.

6. A cushioning mechanism of the friction type which comprises a casing having a closed end and an open end and a friction surface adjacent said open end and of progressively decreasing diameter inward from said end, a plurality of friction shoes in a circular series engaging said surface, a central actuating plunger extending within the group of shoes and having parts interengaging with parts on the shoes, said parts 20 on the shoes and plunger being arranged in tandem lengthwise of said plunger and shoes, a ring at the inner ends of the shoes and interlocked therewith to maintain said shoes in proper circumferentially spaced relation, and a coil spring bearing at one end against said ring and tending to force said ring out of the casing.

7. A cushioning mechanism of the friction type which comprises a casing having a closed end and an open end and a friction surface adjacent 40 said open end and of progressively decreasing diameter inward from said end, a plurality of friction shoes in a circular series engaging said surface, a central actuating plunger extending within the group of shoes and having parts interengaging with parts on the shoes, said parts on said plunger and shoes being of wedge formation and distributed in tandem on said plunger and shoes, a ring at the inner ends of the shoes and interlocked therewith to maintain said shoes in proper circumferentially spaced relation, and a double coil spring bearing against said ring and tending to force said ring out of the casing, both coils of said spring being wound in the same direction.

55. 8. A cushioning mechanism of the friction type which comprises a casing formed with an interior friction surface, a plurality of friction shoes in the casing engaging said surface, a ring at the inner end of the group of shoes and engaging the latter to maintain them in proper circumferentially spaced relation, a central actuating plunger within the group of shoes and having parts interengaging with parts on said shoes, and a helical spring within the casing bearing 60 against said ring and tending to force it out of the casing, said plunger having an end portion of reduced diameter passing through an opening in said ring and entering said spring, said end portion serving as an axial guide for said ring and spring.

9. A cushioning mechanism of the friction type which comprises a casing formed with an interior friction surface, a plurality of friction 70 shoes in the casing engaging said surface, a ring

5 at the inner end of the group of shoes and engaging the latter to maintain them in proper circumferentially spaced relation, a central actuating plunger within the group of shoes and having parts interengaging with parts on said shoes, and a helical spring within the casing bearing at one end against said ring and tending to force it out of the casing, the other end of the spring being anchored.

10. A cushioning mechanism of the friction type, which comprises a casing closed at one end and open at the other, a frusto-conical friction surface on the inner surface of said casing, a plurality of friction shoes engaging said surface and lying side by side, an actuating plunger 15 extending within the group of shoes, said plunger and shoes having interengaging parts provided with contacting surfaces inclined to the longitudinal axis of the casing, the inclination of said surfaces being at self-releasing angles and one 20 end of said plunger projecting out of the casing, said interengaging parts being distributed in tandem lengthwise of said shoes and plunger, a disc at the ends of said shoes provided with means 25 engaging the shoes and maintaining them in proper circumferentially spaced relation, and a helical spring engaging said disc and tending to force it outward.

11. A cushioning mechanism of the friction type which comprises a casing of cylindrical form 30 having a closed end and an open end, flanges at the closed end of the casing lying in a plane transverse to the axis of the casing, a friction surface on the inner wall of the casing, said surface being of progressively decreasing diameter 35 toward the interior of the casing, friction shoes in the casing arranged in a circular series and engaging the friction surface, a central actuating plunger within the series of shoes, said plunger and shoes having interengaging parts, 40 a ring at the inner end of the series of shoes having parts interengaged with individual shoes for maintaining said shoes in proper circumferentially spaced relation, a spring engaging the 45 ring and tending to force it out of the casing, and means limiting the outward movement of said plunger.

12. A cushioning mechanism of the friction type which comprises a casing, friction shoes therein arranged in a circular series, a central actuating plunger extending within the group of shoes, a plurality of interengaging wedging parts on both said shoes and plunger, the parts on said shoes being formed on the inner surfaces thereof, and the parts on said plunger being formed 55 on the outer surface thereof and extending circumferentially of said plunger, said parts on the plunger being disposed along the length of the latter, a ring engaging said shoes and maintaining them in proper circumferentially spaced relation, and a spring within said casing engaging said ring and resisting inward movement thereof.

13. A cushioning mechanism of the friction type which comprises a casing, friction shoes therein arranged in a circular series, a central actuating plunger extending within the series of shoes, transverse wedging parts on the inner surfaces of said shoes, wedging parts extending circumferentially on the outer surface of said plunger, said parts being arranged in series lengthwise of said plunger and shoes, a ring 70 engaging the shoes and maintaining them in proper circumferentially spaced relation, and a 75

spring within said casing engaging said ring and resisting inward movement thereof.

14. A cushioning mechanism of the friction type which comprises a casing, friction shoes therein arranged in a circular series, a central actuating plunger extending within the series of shoes, interlocking wedging parts on the inner surfaces of said shoes and on the outer surface

of said plunger, said parts on said plunger lying in rows extending lengthwise of said plunger, a ring engaging said shoes and maintaining them in proper circumferentially spaced relation, and a spring within said casing engaging said ring and resisting inward movement thereof. 5
